INVENTOR

UNITED STATES PATENT OFFICE.

GEORGE C. EGLEY, OF PHILADELPHIA, PENNSYLVANIA.

KNITTING-MACHINE NEEDLE.

1,077,600.

Specification of Letters Patent.

Patented Nov. 4, 1913.

Application filed May 20, 1912. Serial No. 698,374.

To all whom it may concern:

Be it known that I, GEORGE C. EGLEY, a citizen of the United States, residing in the city and county of Philadelphia, State of Pennsylvania, have invented a new and useful Knitting-Machine Needle, of which the following is a specification.

My invention relates to a new and useful knitting machine needle having a butt, a shank which extends above and slightly below said butt and a spring depending from the lower portion of the shank and offset from the plane of the rear edge of the needle, whereby a space is provided between the inner edge of said spring and the inner wall of the groove when the needle is in operative position. By extending the shank slightly below the butt, a bearing point is provided so close to the butt that improper outward movement thereof is prevented.

It further consists of other novel features of construction, all as will be hereinafter fully set forth.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a knitting machine needle embodying my invention, and a partial sectional view of a portion of a cylinder with the needle in place in a groove thereof. Fig. 2 represents a view of the parts shown in Fig. 1 in a slightly different position. Fig. 3 represents a front elevation of the needle. Fig. 4 represents a perspective view of a portion of the needle showing a solid butt and a spring depending from the lower portion of the shank. Fig. 5 represents a similar view showing a butt formed by bending the material of the needle. Fig. 6 represents a view showing a form of spring, offset from the plane of the rear edge of the needle.

Similar numerals of reference indicate corresponding parts in the figures.

Referring to the drawings:—I have found in practice, in the knitting machine needles wherein the spring is in substantially the

same plane as the rear edge of the needle, that when any pressure or tension is exerted on the needle, which sometimes occurs to cause the upper portion of the needle to move outwardly, the lower end thereof, and so the spring, is forced against the rear wall of the groove in which the needle is situated, causing a binding of the spring and preventing proper action thereof. In addition, when the lower portion of the spring is forced into engagement with the inner wall of the groove, it will result in moving the butt outwardly too far, that is, into such a position that it touches the inner wall of the cam cylinder, which is not only injurious to the latter but will also in cases bend the butt, so spoiling the needle and preventing proper operation of the same. My invention is designed to overcome this defect, as will be hereinafter set forth.

1 designates a knitting machine needle, the same being provided with the shank 2 having a suitable hook 3 and pivoted latch 4, a suitable portion of which is adapted to co-

operate with the hook. 5 designates a butt projecting from the shank, which latter has a suitable portion extending slightly below said butt. 6 designates a spring which depends from the lower portion of said shank and which spring is offset or cut away as at 7 starting substantially at the lower end 8 of said shank, which portion 8 forms a bearing point, all as will be hereinafter described. As will best be understood from Figs. 3 and 4, it will be seen that the spring is preferably formed by thinning the material forming the needle and that said spring is reversely curved at 9 and 10 in a plane transverse to that of the thickness of the needle, whereby I can provide a smooth surface for engagement with the side walls of the groove, which will prevent scratching or injuring of the walls thereof, which would be of disadvantage in that the needles may not be properly guided.

It will be seen more particularly from Figs. 1 and 2, when the needle is in operative position and resiliently held in place by the binder or spring 11, that the rear edge of the shank bears against the inner wall of the groove and that a space is provided between the inner edge of the spring and the said rear wall, whereby it will be understood that when tension or any pull is exerted on the needle, which will cause the same to move slightly outward in the groove,

as seen in Fig. 2, the lower end 8 of said shank forms a bearing point or fulcrum, so that while the spring 6 is caused to approach the rear wall of the groove, it will not come in contact therewith since the tension or power exerted on the needle will not be sufficient for this purpose, so that the spring will always be free to perform its proper function, that is for proper engagement with the side walls of the grooves. In addition, by forming the bearing point, only slightly below the butt, the point of leverage is so small that when the upper portion of the needle is moved slightly outward, there is comparatively no outward movement of the butt, so that it is free at all times of the inner wall of the cam cylinder and is always in proper position for operation.

It will be understood that any suitable form of butt may be employed, that the

needle may be of any suitable material, and that any suitable means for offsetting the spring may be employed to accomplish the desired result.

Having thus described my invention, what I claim as new and desire to secure by Letters Patent, is:—

A knitting machine needle having a butt, a shank which extends above and slightly below said butt to form a bearing point, and a spring depending from the lower portion of said shank and offset from the plane of the rear edge thereof, at said bearing point, and curved in a plane transverse of that of the thickness of the needle.
